AMPLIFIER.

Application filed April 4, 1921, Serial No. 458,628, and in Germany December 2, 1919.

(GRANTED UNDER THE PROVISIONS OF THE ACT OF MARCH 3, 1921, 41 STAT. L. 1313.)

Amplifiers with several amplifying stages are known in which each stage includes a special or separate cathode. The stages are usually independent of each other and an additional amplifier is utilized for adding each amplifying stage. When several stages are obtained from one tube the tube would be correspondingly large on account of numerous cathodes employed. If an exact adjustment of the cathode temperatures is to be made possible, the cathodes must be heated separately. It is indeed also known to arrange the cathodes one behind the other, connected in series, and to heat them in common. But with a given heating current the temperature of an incandescent wire is to a very great extent dependent upon the heat emitted by the filament by radiation and conduction. Consequently it is very difficult with this arrangement to obtain approximately equal temperatures of the cathodes with the same heating current.

An object of the invention is to provide an amplifier in which several amplifying steps may be accomplished in a single tube, having a single cathode and a plurality of anodes and grids.

Other objects consist in the provision of the improved combinations of parts and details of construction, all as will be more fully set forth hereafter and be particularly pointed out in the appended claims.

In order that the invention may be more clearly understood attention is hereby directed to the accompanying drawings illustrating diagrammatically various forms of construction, by way of example, which are included within the invention.

In the drawings, Figure 1^a represents a two-stage amplifier with both stages contained within a single tube with a resistance coupling between the stages; Figure 1^b is a modification thereof;

Figs. 2^a and 2^b are further modifications thereof;

Fig. 3 is a similar two-stage modification having a transformer coupling between the stages;

Fig. 4 is a cross section taken through a four-stage amplifier, all the stages being con-

tained within a single tube, the wiring connections being omitted; and

Fig. 5 is a wiring diagram of the amplifier shown in Fig. 4, the connections for two stages only being indicated to prevent confusion.

In the construction shown in Figs. 1^a to 2^b inclusive, the cathode *k* is shown as arranged in the middle of the tube. At opposite sides thereof, grids *g*¹ and *g*² are positioned with anodes *a*¹ and *a*² respectively, grids *g*¹ and *g*² being interposed between anode *a*¹ and the cathode, and the anode *a*² and the cathode respectively. The current to be amplified is considered as flowing through the primary of transformer *T*, the secondary of which is connected to cathode *k* and the first grid *g*¹, producing the potential drop across the space between grid *g*¹ and cathode *k*, which potential drop is indicated on the drawings as *eg*'. This input potential causes an amplified current to flow in the first anode or plate circuit including anode *a*¹ and cathode *k*. This serves to correspondingly increase the potential drop between the grid *g*² of the second amplifying stage, and cathode *k*, and this correspondingly produces greater variations of resistance and current between the anode *a*² of the second stage and the cathode *k*.

The coupling of the two-stages of amplification may be effected in any known manner. In Figs. 1^a to 2^b inclusive, a resistance coupling is shown and in Fig. 3 an inductive coupling.

The variations of current thus produced in the anode circuit of the first stage are, in the case of inductive coupling (Fig. 3), transmitted in a known manner by the transformer *T* to the second amplification stage as increased variations of potential *eg*² between the cathode and grid *g*². The varying potential on grid *g*² causes an amplified current to flow in the second anode circuit which, as shown, includes a useful resistance *N*, the output circuit being considered as led-off from the terminals of this resistance. In this arrangement both anode circuits can be supplied from a single constant source of potential *E*, included in the common portion

- of the two anode circuits. This same source may, as shown, be used to supply the heating current for the cathode, through the circuit indicated, including the resistance shown at H. In this figure also a small resistance w is shown as inserted between battery E and the cathode, the potential drop through this resistance being used to obtain a negative bias at the grids.
- 10 Considering now a tube having resistance coupling between the two stages as shown in Fig. 1^a, the arrangement of the cathode, anodes and grids is the same as has been described. A heating circuit for the cathode is shown as extending through connection 1 and separate heating battery E^x.

The first anode circuit extends from anode a', by conductor 2 to battery E' and resistance wp shunting the same, and then through the coupling resistance w' to cathode k. This resistance w' is suitably of the order of values of the average internal anode-cathode resistance of the first amplifying step. Variations of the input potential drop eg' cause, because of variations of resistance between a' and k, variations of the distribution of potential drop in the first anode circuit, as between the internal path a'—k and the external resistance which may be considered as resistance w' . The potential variations across resistance w' are transferred to the grid g^2 and are effective as potential variations between this grid and cathode k as indicated at eg^2 . The connections from the terminals of the resistance w' to cathode k and grid g^2 are shown in Fig. 1^a as conductors 3 and 4. The second anode circuit is shown in Fig. 1^a as including the separate source E² and the resistance N, across the terminals of which the output circuit of the tube may be connected.

In the connection shown by Figs. 1^a and 1^b on the one hand and Figs. 2^a and 2^b on the other hand, there is a difference, namely, that the potentials transmitted to grid g^2 are negative in the first case and are positive in the second case. In both cases the potentials impressed on grid g^2 are comparatively large because of the high anode potentials which are used on account of the internal properties of the tubes. That is to say, resistance couplings are used between the stages of amplification; the anode potentials are high in comparison with anode potentials which would be used with transformer couplings. It will, therefore, often be necessary to diminish the average potentials impressed upon grid g^2 .

60 This can, for example, be effected by the insertion of an auxiliary potential e^2 , with this potential being of a sign which is opposed to that of the drop of potential across the terminals of the coupling resistance with which it is connected, (Figs. 1^a and 2^a). Potential eg^2 , impressed on grid g^2 , is then

always equal to the drop of potential e^1 across the coupling resistance w' less potential e^2 . In the arrangement shown in Fig. 1^a, there is an advantage in that the battery E' can be divided by a sliding contact on resistance wp , the drop of potential from the upper terminal of resistance wp , as shown in Fig. 1^a, to the sliding contact being the drop of potential e^2 referred to. As noted, a separate source of potential E² is required for the second anode circuit.

The variations of current in the second anode circuit are reversed in direction in comparison with those of the first anode circuit, and, accordingly, the internal resistance of the two stages a'—k and a"—k, connected in parallel with the source E¹ would work counter to each other, if both anode circuits were simultaneously fed from source E¹. Therefore, there would be smaller potential drop variations across the resistance w' and across the path a'—k of the tube because of this counter action of the two anode-cathode paths, and, accordingly, the variations of current in the second anode circuit would likewise be correspondingly smaller.

In the connection shown by Fig. 2^a, this disadvantage does not arise with a common source of anode potential, since resistance w' is no longer in the common portion of the anode current circuits, and the resistance w^2 whose voltage drop is utilized for the production of a suitable bias at grid g^1 has so little resistance that its voltage drop is negligible. This connection also permits the heating of the cathode from the battery E. In Fig. 2^a, a separate source of potential e^2 is shown as connected in the conductor extending to grid g^2 , this source having its terminals connected oppositely to those of the source E, with which it is connected in series with the resistance w' .

In the connections shown by Figs. 1^b and 2^b, the condenser C is substituted for the auxiliary potential e^2 . This condenser C, if well insulated, possesses a practically infinite resistance for direct current, but with a smaller resistance for alternating current, which depends on its capacity and on the frequency of the current. The average voltage e^1 comprises in part a direct current voltage which is distributed in accordance with the ohmic resistance of the path traversed, while the other component of voltage e^1 comprises an alternating potential which is distributed in accordance with the alternating current resistance of condenser C and the path g^2 —k of the tube. In order to obtain definite proportions for the direct current voltage distribution, ohmic resistances w^3 and w^4 are connected up in parallel to condenser C and the path g^2 —k, Figs. 1^b and 2^b, resistances w^4 and w^3 being preferably balanced. These resistances w^3 and w^4 are, of course, properly chosen for the po-

tential drop required across the same. A suitable bias can then be placed on gird g^2 , by a connection from the terminal of resistance w^2 , through resistance w^3 , to grid g^2 .
 5 The resistance w^4 provides a shunt around condenser C for carrying the direct current component to the voltage which is to be carried to grid g^2 .

The number of amplifying steps with a common cathode is not limited to two. In Figs. 4 and 5 a form of construction is shown with four amplifying steps, this construction being suitable for connection with resistance coupling. It will be noted that in such a case the increase of the grid potential from one step to the next does not depend upon the absolute strength of current in the different anode circuits, but upon the relative current variations in the anode circuits.
 20 Accordingly, comparatively small anodes may be used in the first three amplifying steps, with, however, a larger anode in the fourth amplifying step, since the variations of potential are here to be converted into variations of output current.

In the construction indicated in Fig. 4, a common cathode k is shown at the center of the tube with three small anodes, a^1 , a^2 and a^3 , each shown as surrounded by a tubular grid g^1 , g^2 and g^3 , respectively. A larger anode, a^4 , is shown, as semi-circular in cross section, on the opposite side of cathode k with its grid g^4 of semi-circular section interposed between the cathode and anode a^4 .

35 Protecting grid shaped auxiliary electrodes h^1 , h^2 and h^3 are shown as surrounding grids g^1 , g^2 and g^3 respectively, while a similar protecting electrode h^4 , semi-cylindrical, is shown as interposed between cathode k and grid g^4 . These protecting electrodes h^1 , h^2 , h^3 and h^4 are provided for the purpose of preventing interaction between the various amplifying stages of the tube, that is, these auxiliary electrodes serve to diminish the passage of lines of force from one amplifying step to an adjacent amplifying step. Suitable constant potentials are impressed upon grids h^1 , h^2 , h^3 and h^4 , which potentials may be either positive or negative, as desired. The use of such protecting electrodes is illustrated only in Figs. 4 and 5, but they may be used in the constructions illustrated in the other figures as well, although, of course, there is not so much need

55 for the same when two step amplification only is used. Protection against this action can be obtained by separating the grids of the different steps a sufficient distance from each other, but this cannot be practically accomplished when, say, three or four amplifying steps are mounted in a single tube without having a tube of undesirable large size, and accordingly the protection by means of the auxiliary electrodes h^1 , h^2 , h^3 and h^4 is deemed preferable. The va-

rious electrodes used may be of desired forms, such for example as the concentric arrangement indicated in Fig. 4, the invention, however, not being limited in this respect. It may also be noted in Fig. 4 that the cathode k is represented as larger in cross section than in Figs. 1^a to 3^a inclusive, this for the reason that the lines of force leading from the cathode to the various anodes in Fig. 4 will be reduced by the protecting electrodes h^1 — h^4 and accordingly this loss should be compensated by a correspondingly large cathode.

Referring to the wiring connections for Fig. 4, shown in Fig. 5, two steps of amplification have been omitted for the purpose of simplifying the diagram. The cathode k is illustrated as a linear unit, so that two separated points of connection to the same may be illustrated for convenience. The heating circuit for the cathode is illustrated as extending through resistance H and through battery E' and resistance w^2 . The input is represented as feeding through a transformer coupling, T, which connects to grid g^1 and to cathode k . The anode circuit of the first stage extends from anode a^1 through resistance w' , battery E' and resistance w^2 to cathode k . This provides the varying potential drop across the coupling resistance w' , which impresses a corresponding varying potential across the space between cathode k and the grid of the next amplifying stage which is represented as grid g^4 , the connection to grid g^4 extending through the counter-acting source of potential e^2 , as described above. The anode circuit for the second stage illustrated, extends from anode a^4 through resistance N and battery E' back to the cathode k . The protecting electrodes h^1 and h^2 are illustrated as connected together in series and through an auxiliary battery eh, which impresses the desired potential on electrodes h^1 and h^2 , back to cathode k . It will be understood that the connections for the amplifying steps involving anodes a^2 and a^3 and grids g^2 and g^3 have been omitted for simplicity and the connections shown in Fig. 5, as if electrodes a^4 and g^4 were in the next amplifying step to electrodes a^1 and g^1 . If the connections for all of the steps were indicated, those which have been just described would be duplicated.

What we claim is:

1. A multiple-stage amplifier, comprising a single evacuated container, a single integral undivided heated cathode, common, as a whole, to the several stages of amplification, and a plurality of anodes and grids in said container, spaced away from the cathode and from each other, and all arranged outside the entire cathode, connections for impressing an input potential difference across the cathode and first grid, external circuits connect-

ing each anode with the cathode, and means for coupling the anode-cathode external circuit of each stage except the last with the cathode and grid of the next stage.

5. 2. A multiple-stage amplifier, comprising a single evacuated container, a single undivided heated cathode, common, as a whole, to the several stages of amplification, and two anodes and two grids, in said container, 10 spaced away from the cathode and from each other and all arranged outside the entire cathode, connections for impressing an input potential difference across the cathode and first grid, an external circuit connecting the first-stage anode with the cathode, means for impressing drop of potential in said circuit across the cathode and grid of the second stage, and an external circuit connecting the second stage anode with said cathode.
- 0 3. A multiple-stage amplifier, comprising a single evacuated container, a single undivided heated cathode, common, as a whole, to the several stages of amplification, and two anodes and two grids in said container, 25 spaced away from the cathode and from each other and all arranged outside the entire cathode, connections for impressing an input potential difference across the cathode and first grid, an external circuit connecting the first-stage anode with the cathode, said circuit including a resistance, means for transferring drop of potential in said resistance across the cathode and grid of the second stage, and an external circuit connecting 30 the second stage with said cathode.

4. A multiple-stage amplifier, comprising a single evacuated container, a single integral undivided heated cathode, common, as a whole, to the several stages of amplification, and a plurality of anodes and grids in 40 said container, separated by vacuous space from the cathode and all arranged outside the entire cathode, said cathode being of uniform cross-sectional area throughout, 45 connections for impressing an input potential difference across the cathode and first grid, an output circuit connected to the cathode and last anode, external conductive circuits connecting each anode with the cathode, means for impressing direct current po-

tential upon each of said circuits, and means for transferring potential variations in each anode-cathode circuit except the last to the grid of the next stage.

5. A multiple-stage amplifier, comprising 55 a single cathode common to the several stages of amplification, a plurality of anodes and grids in said container, connections for impressing an input potential difference across the cathode and first grid, circuits 60 connecting each anode with the cathode, means for transferring potential variations in each anode-cathode circuit to the grid of the next stage, auxiliary screening electrodes 65 interposed between said grids and cathode, and means for impressing a constant potential upon said screening electrodes.

6. A multiple-stage amplifier, comprising a single evacuated container, a cathode and a plurality of anodes and grids therein, 70 connections between said electrodes for producing a plurality of amplification stages within the tube with electron-discharge paths between the cathode and the several anodes, and means, comprising screening electrodes, 75 for reducing reaction between the electron-discharge paths of the several stages.

7. As a new article of manufacture, a multiple-stage amplifier, comprising a single evacuated container, a centrally positioned 80 cathode, and a plurality of anodes with grids surrounding the same, and screening electrodes surrounding said grids, all spaced from said cathode, all within said container.

8. As a new article of manufacture, a multiple-stage amplifier, comprising a single evacuated container, a centrally positioned cathode, a plurality of anodes of comparatively small size with grids surrounding the same, on one side of the cathode, a larger 90 anode of semi-cylindrical section, on another side of the cathode, with a grid interposed between the same and said cathode, all within said container.

In testimony whereof we affix our signatures.

JOSEPH MASSOLLE.
